UNITED STATES PATENT OFFICE.

HENRY M. RAMSAY, OF ALTOONA, AND JUSTUS A. RICKABAUGH, OF PITTSBURGH, PENNSYLVANIA.

UNCOUPLING DEVICE FOR CAR-COUPINGS.

1,087,509.

Specification of Letters Patent.

Patented Feb. 17, 1914.

Application filed February 21, 1913. Serial No. 750,026.

To all whom it may concern:

Be it known that we, HENRY M. RAMSAY, of Altoona, in the county of Blair and State of Pennsylvania, and JUSTUS A. RICKABAUGH, of Pittsburgh, in the county of Allegheny and State of Pennsylvania, have invented certain new and useful Improvements in Uncoupling Devices for Car-Couplings; and we do hereby declare the following to be a full, clear, and exact description of the invention, such as will enable others skilled in the art to which it appertains to make and use the same.

This invention relates to improvements in uncoupling devices for car couplings,—the object of the invention being to so construct devices of this character that they will readily adapt themselves to the movements of which the coupling-head is susceptible and so that the parts will always be in position to be operated for raising the locking block or pin without danger of binding or of undue friction even though the member which directly engages the locking block or pin may become bent.

A further object is to provide uncoupling devices which can be mounted in and to a certain extent concealed by the end-sill of a steel car, or which can be applied to the inside face or the outside face or just back of the end sill.

A further object is to so construct uncoupling devices that they may be operated without necessity for a trainman to enter between cars, and so that, when manipulated from the side of a car, the operator will always pull outwardly or away from the car and thus obviate danger of falling between the cars in case of slipping.

A further object is to so construct uncoupling devices that they may be operated either from the side or the top of the car.

A further object is to construct the devices in such manner that they may be made to operate either a top lever, bottom lever, or side operating coupler, without any material changes in the construction of the mechanism.

With these objects in view, the invention consists in certain novel features of construction and combinations of parts as hereinafter set forth and pointed out in the claims.

In the accompanying drawings, Figure 1 is a view of a portion of a car showing the

application of our improvements. Fig. 2 is a view on the line $x-x$ of Fig. 1, Fig. 3 is a view on the line $y-y$ of Fig. 1; Fig. 4 is a view showing the devices in which a bottom instead of a top lever is employed. 60

1 represents the hollow or channeled end-sill of a car; 2 the draft sills, and 3 the coupling-head provided with a draw-bar passing freely through an elongated opening in the end-sill and pivotally connected 35 to cross-bars or plates 4—5 secured to the draft-sills.

Suitable bearings 6—7 are secured to the end-sill for the accommodation of a shaft 8 passing through the front end wall of the 70 sill. The outer end of this shaft is bent upwardly, forming an arm 9 which is made tubular to receive freely a shank 10 depending from the short member 11 of an L-shaped lever 12. The long arm of lever 12 75 projects over the rear portion of the coupling head and passes freely through elongated eyes or loops 13 on the upper end of the locking block or pin 14. The rear end of the shaft 8 which may terminate within 80 the hollow or channel end-sill 1 has secured thereto, a bell-crank-lever 15. The arm 16 of this bell crank has attached thereto one end of a rod 17,—said rod extending beyond one end of the end-sill and 85 provided with a handhold 18 to permit an operator to manipulate the devices from the side of the car. The arm 19 of the bell-crank 15 is horizontally disposed and to its 90 free end, the lower end of a rod 20 is attached,—said rod extending upwardly above the top end of the car, where it is provided with a suitable handhold 21 whereby the operator may manipulate the devices 95 from the top of the car.

It is apparent that when the shaft 8 is turned by the manipulation of either of the operating rods, the upwardly projecting arm of said shaft will be moved laterally and the horizontal arm or lever 12 moved upwardly 100 in the arc of a circle, sliding freely through the eyes or loops 13 on the locking block or pin and causing the latter to be raised to release the knuckle of the coupling-head. By providing a telescopic and rotary connection between the arm 9 of the shaft 8 and the L-shaped lever 12, the latter will always adapt itself to the position or displacement of the coupling-head and its locking block or pin and permit the free manipu- 105 110

lation of the uncoupling devices to raise the locking-block or pin without friction or binding between the parts even though the long arm of the L-shaped lever 12 which engages the locking-block or pin, may become bent or more or less distorted.

In the above description, portions of the devices are referred to as being located within a hollow end sill, but it is evident that these devices may be applied to the outside of the end sill or rearwardly of the same.

In Figs. 1 and 2 of the drawing, a top lever 12 is employed to engage the loops on the top of the locking block or pin but this arrangement may be reversed, and the lever made to operate as a bottom lever as shown at 12^a Fig. 4,—in which event, loops 13^a will be provided at the bottom of the locking block or pin for the passage of said lever.

With the use of our improvements, the uncoupling devices may be operated either from the side or from the top of the car and without necessity for the trainmen to enter between the cars. When operated from the side, the pull will be in an outward direction, away from the car, so that in case of slipping, there will be no danger of the trainman falling between the cars. When the devices are operated from the top of the car, the trainman may occupy the same platform on which he stands to operate the hand brake,—thus making it possible for the trainman to uncouple his car and still remain at his hand brake,—a feature of great safety, especially in yards where it usually has been necessary for the brakeman to climb down and uncouple his car and then climb up to his brake mast.

Having fully described our invention what we claim as new and desire to secure by Letters-Patent, is:—

1. The combination with the end sill of a car and a car coupling having a locking block or pin, of a rock shaft mounted trans-

versely with respect to the end sill and provided at its outer end with a tubular arm lying approximately parallel with the front wall of the sill, a lever having a revolute connection with said tubular arm and having movable connection with the locking block or pin, another arm on said rock shaft, and an operating rod connected with said last-mentioned arm. 50

2. The combination with the end sill of 55 a car and a car coupling having a locking block or pin, of a rock shaft mounted transversely with respect to the end sill and provided at its outer end with a tubular arm lying approximately parallel with the front 60 wall of the sill, a lever having a revolute mounting in said tubular arm and movably connected with the locking block or pin, another arm on said rock shaft rearwardly of the front face of the end sill, and an 65 operating rod disposed behind the front wall of the end sill and connected with said last mentioned arm.

3. The combination with the end-sill of 70 a car and a car coupling provided with a locking block or pin having an eye at its upper end, of a shaft mounted in said end-sill and provided beyond the end sill with an upwardly projecting arm, an L-shaped lever loosely connected with said arm and 75 having its long member passing freely through the eye on the coupling block or pin, a bell-crank secured to said shaft within the end sill, and manually operable rods connected respectively to the respective arms 80 of said bell-crank.

In testimony whereof, we have signed this specification in the presence of two subscribing witnesses.

HENRY M. RAMSAY.
JUSTUS A. RICKABAUGH.
